UNITED STATES PATENT OFFICE

GEORGE NAISMITH, OF PITTSBURGH, PENNSYLVANIA.

BOILER SETTING.

Application filed March 9, 1922. Serial No. 542,376.

To all whom it may concern:

Be it known that I, GEORGE NAISMITH, a citizen of the United States, residing at Pittsburgh, in the county of Allegheny and State of Pennsylvania, have invented certain new and useful Improvements in Boiler Setting, of which the following is a specification.

My invention relates to an improvement 10 in boiler setting, and more particularly to the construction of the enclosing walls of the furnace, with a view to providing for a hot air supply for the fuel. It has in view to pre-heat the incoming air prior to its addition to the furnace chamber, and to then 15 distribute it across the combustion area, through the water tube zones, and finally in a reversed surrounding series of flues to the final outlet connection, in such a manner as 20 to utilize the waste heat to the best advantage.

The invention is illustrated in one preferred form in connection with the combustion of pulverized fuel as shown in the 25 drawings herewith, in which:

Fig. 1 is a vertical sectional view through a boiler setting showing the air supply conduits and ports, on the section line I—I of Fig. 2;

Fig. 2 is a partial horizontal section on the line II—II of Fig. 1;

Fig. 3 is a transverse vertical section on the line III—III of Fig. 1;

Fig. 4 is a partial similar section on the 35 line IV—IV of Fig. 2.

The boiler construction, *per se*, is not necessarily of any particular construction, the invention being capable of utilization with practically any standard water tube 40 type. In the drawings, I show a typical arrangement utilizing an upper water inlet and steam supply drum 2, connected by a bank of tubes 3 to a lower mud drum 4, with which, by additional circulating banks 45 of tubes 5—6, is connected another upper drum 7. Drums 2 and 7 are water and steam drums and are connected with each other, as shown, through an intervening steam and water separating drum 8, by tubes 9—10, a drain tube 11, and a cross-over tube 12, similar to the construction shown in the co-pending application of Donald M. Naismith, Serial No. 444,678.

It will be understood that the invention 50 does not necessarily depend on the presence

of baffles, but that suitable baffling walls may be provided, if desired, to control the circulation between the tubes for best results as to steam production, as will be readily appreciated by those familiar with the art, together with other necessary features of construction, super-heater, etc., not herein specifically shown or described.

The front and back walls 13—14 extend inwardly towards the interior furnace and boiler chamber by series of transverse partitions 15, which connect the outer walls 13—14 with inner walls 16—17 respectively, and similar horizontal outer and inner walls 18—19 form continuations thereof, with 70 corresponding partitions 15^a, as shown. Intervening flues 20 for heated air and flues 21 for waste gases alternate with each other across the width of the furnace walls 13—16, 14—17, and 18—19 respectively, each such 75 flue being separated from the next adjacent one by the partition 15—15^a, providing a continuous series of alternating air heating and waste gas flues occupying substantially the full available width of the setting.

The waste-gas flues 21 are connected at the top on the outlet side by a common cross flue or conduit 22 opening to a stack connection 23, preferably provided with a 80 damper controlling valve 24.

The heating flues 20 for incoming air at the air supply side are connected at the tops by individual conduits 25 with a common air supply pipe 26, for furnishing air, preferably under pressure, from the outside. 85 Fuel air, thus supplied, passes downwardly through flues 20, then across through the base, and upwardly through the opposite front wall 13—16. The inner partition wall 16 is provided with a vertically arranged series of branch inlet ports 27 registering with each vertical air supply flue 20 and extending for substantially the full depth of the furnace cavity 28, providing for supply of hot air at various levels consecutively 90 throughout its height.

Fuel, in the form of pulverized coal, is admitted through the series of openings 29 in the roof of the furnace, or in any other suitable manner, whereby to pass downwardly into the combustion chamber 28, a hearth 30 of any suitable form being preferably provided at the bottom. The incoming hot air from ports 27 combines with the coal in combustion, and, after circulating 100

through the tube spaces, etc., the resulting gases and products of combustion pass outwardly through similar series of ports 31 into and downwardly through the waste gas flues 21.

As previously stated, flues 21 alternate with flues 20, so that the hot products of combustion pass from ports 31 downwardly, across underneath the bottom, and then upwardly towards the final outlet stack. They thus impart a preheating action through the walls and partitions 15 to the incoming air passing in the same direction through the alternating flues 20, so that as it finally emerges through ports 27 into the combustion chamber, it is of the desired high temperature. The resulting effect is to produce efficient and complete combustion of the fuel, and a corresponding rapid generation of steam.

It will be understood that the size, number, or arrangement of the flues 20 and 21 and of the ports 27 and 31 may be varied according to good practice, as by enlarging or reducing the size of the ports by removal or addition of bricks, etc. All such changes are presumed to be within the skill or judgment of the builder, to suit the construction and operation of the boiler, or as affected by local conditions, and do not constitute a departure from the invention as expressed in the following claims.

What I claim is:

1. In boiler construction, the combination with the heating elements of a water tube boiler, of a surrounding structure including opposite end walls, a connecting base, and a cover providing an enclosing combustion and circulation cavity for said heating element and for fuel combustion and having series of alternating air and waste gas flues, with air supply ports opening into the cavity at one side and waste gas ports leading from the cavity at the other side said flues extending in parallelism throughout the end walls and base.

2. In boiler construction, the combination with the heating elements of a water tube boiler, of a surrounding structure including opposite end walls, a connecting base, and a cover providing an enclosing combustion and circulation cavity for said heating element and for fuel combustion and having series of alternating air and waste gas flues, with air supply ports opening from the air flues into the cavity at one side and waste gas ports leading from the cavity at the other side into the waste gas flues said flues extending in parallelism throughout the end walls and base.

3. In boiler construction, the combination with the heating elements of a water tube boiler, of a surrounding structure including opposite end walls and a connecting base providing an enclosing combustion and cir-

culation cavity for said heating element and for fuel combustion and having series of alternating air and waste gas flues extending downwardly through one end wall, then across under the boiler, and then upwardly through the other end wall, with air supply ports opening from the air flues into the cavity at one side and burnt gas ports leading from the cavity at the other side into the gas flues.

4. In boiler construction, the combination with the heating elements of a water tube boiler, of a surrounding structure including opposite end walls and a connecting base providing an enclosing combustion and circulation cavity for said heating element and for fuel combustion and having series of alternating air and waste gas flues extending downwardly through one end wall, then across under the boiler, and then upwardly through the other end wall, with air supply ports opening from the air flues into the cavity at one side and waste gas ports leading from the cavity at the other side into the gas flues, means for introducing air to the gas flues, means for carrying off the products of combustion from the several gas flues at the other side.

5. In boiler construction, an enclosing setting provided with oppositely arranged walls and a transverse connecting base having series of alternating air and gas circulation flues extending continuously there through with intervening separating partitions, and having air ports opening from the air flues through the wall at one side to the interior, and gas ports opening from the interior to the gas flues through the wall at the opposite side.

6. In boiler construction, an enclosing setting provided with oppositely arranged walls and a transverse connecting base having series of alternating air and gas circulation flues extending continuously there through with intervening separating partitions, and having air ports opening from the air flues through the wall at one side to the interior, and gas ports opening from the interior to the gas flues through the wall at the opposite side, with an air supply conduit opening into the upper portions of the several air flues at one side and a waste conduit leading off from the upper portion of the several gas flues at the other side.

7. In boiler construction, the combination with the heating elements of a water tube boiler, of a surrounding structure including opposite end walls and a continuous hollow connecting base providing an enclosing combustion and circulating chamber for said heating elements and for fuel combustion, and having waste gas flues leading upwardly from said base between alternating gas heating flues extending through the front wall

throughout the entire height of the combustion chamber and provided with an uppermost outlet conduit.

8. In boiler construction, the combination with the heating elements of a water tube boiler, of continuous surrounding front, back, end, and bottom walls and a covering providing an enclosing combustion and circulating chamber for said heating elements and for fuel combustion, means for conducting pre-heated air through the front wall to the combustion chamber, consisting of alternating air flues opening inwardly to the combustion chamber between alternating products of combustion flues, and means for introducing fuel from the top of the chamber between the inwardly opening hot air supply and the heating elements of the boiler.

- 20 9. In boiler construction, the combination

with the heating elements of a water tube boiler, of a continuous surrounding vertical and horizontal wall providing an enclosing U-shaped combustion and circulation cavity for said heating elements and for fuel combustion, and having continuous parallel alternating series of air circulating and waste gas circulating flues extending downwardly through one vertical wall portion, laterally through the horizontal portion, and upwardly through the other vertical wall portion, said vertical wall portions having inwardly and outwardly leading ports respectively at opposite sides of the combustion chamber for pre-heated air and products of combustion respectively.

In testimony whereof I hereunto affix my signature.

GEORGE NAISMITH.
